WILLIAM EVENSEN AND GEORGE L. HERMANSON, OF CHICAGO, ILLINOIS, ASSIGNEES
TO GOSS PRINTING PRESS COMPANY, A CORPORATION OF ILLINOIS.

QUICK LOCK-UP FOR PLATE CYLINDERS.

Application filed December 4, 1925. Serial No. 73,209.

Our invention relates to printing presses, and more particularly to a quick lock-up for plate cylinders, in which the clips can be quickly changed to different positions, to correspond with different number of columns, or sheet widths, which may be desired to be printed on a newspaper, or other printed product.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations, articles of manufacture, and improvements herein shown and described.

The accompanying drawings, referred to herein and constituting a part hereof, illustrate one embodiment of the invention, and together with the description, serve to explain the principles of the invention.

26. Of the drawings:—

Fig. 1 is a plan view of the end of a plate cylinder, showing a printing plate locked in position;

Fig. 2 is a fragmentary end elevation of a part of the printing plate cylinder shown in Fig. 1, a portion of the cylinder being broken away;

Fig. 3 is a fragmentary vertical section, substantially on the line 3—3 of Fig. 2, through the plate cylinder, showing the clips adjusted for a seven column paper, or other printed product;

Fig. 4 is a fragmentary vertical section, similar to Fig. 3, but showing the parts adjusted to print a six column newspaper, or other printed product;

Fig. 5 is a detail sectional view showing one of the clip rods in its unlocked position;

Fig. 6 is a transverse sectional view on line 6—6 of Fig. 5.

In printing a newspaper, or other printed product, it is frequently necessary to change the clips, holding the plates on the cylinder, so that a newspaper, or other printed product, of a different number of columns can be printed. For purposes of illustration we will refer to Fig. 3 as showing the position of the parts to print a newspaper of seven columns, and Fig. 4 the position of the clips

to print a newspaper, or similar product, of six columns. While we will refer to printed products of six or seven columns, it is to be understood that these are simply illustrative, for our invention is adapted to be employed to make any suitable adjustment for different sheet widths, as for example, 8, 7 or 6 columns. It is also adapted to make adjustments for different column widths; for example for a sheet of 8 columns, 12 ems, to a sheet of 8 columns 13 ems, or any other suitable adjustment can be made.

In the form of our invention, shown by way of illustration, 1 is any suitable form of plate cylinder upon which is secured the printing plate 2 by the outer clips 3, 3 four such clips being shown in Fig. 1. Co-operating with these outer clips 3, 3 are the inner clips 4, 4, one being shown in Figs. 3 and 4. It is understood that there are four of such inner clips 4 for each printing plate, making eight clips in all for each printing plate.

Mounted on the periphery of the plate cylinder 1, are a plurality of longitudinally extending grooves 5 within each of which slide an outer and an inner clip 3 and 4, and also a clip rod 6. This clip rod 6 is formed of two parts 7 and 8. The end of the portion 7 is provided with female threads 9 to cooperate with the male threads 10 on the portion 8. The exterior of the portion 7 of the clip rod 6 is provided with screw-threads 11 on which are mounted the stops 12 and 13. These stops are preferably in the form of nuts and are held in their adjusted position by the respective set screws 14, 14.

The portion 8 of the clip rod 6 is also provided with a spline 15 to receive the end of the screw 16 which is threaded in the part 17 of the plate cylinder 1. The end of the portion 8 of the clip rod is provided with male threads 18 to cooperate with the stops 19 and 20, which are preferably in the form of nuts. A check nut 21 may also be employed.

The threads 10 on the inner portion 8 of the clip rod 6 are one-half the pitch of the threads 11 on the exterior of the portion 7 of the clip rod. The interior of the outer clips 3 are provided with female screw-threads 22 to cooperate with the male threads 11 on the portion 7. The inner clip

4 has a smooth bore 23 and rests loosely upon the screw-threads 18 on the portion 8 of the clip rod 6.

The portion 7 of the clip rod is provided with a shoulder 24, the end 25 being preferably formed square, or non-circular, to be engaged by a spanner, monkey wrench, or other tool. Near the squared end 25, we secure a collar 26 by a set screw 27 to engage with the coil spring 28 in the unlocked position of the clip rod, as will be more fully hereinafter described.

The check nut 12 is secured on the clip rod 6 for a paper or other printed product of, for example, 7 columns, and the check nut 13 is secured on the clip rod 6 for a different number of columns, for example, 6 columns.

The lock-up plate 29, supported by the guide studs 30, 30 is provided with a recess 31 to receive the end of the clip rod 6, and the coil spring 28 which bears against the shoulder 24 on the clip rod 6 and one of the end plates 30', which plates are secured to the face of the lock-up plate 29 by the screws 31', 31", there being, in the form shown, a separate end plate for each clip rod 6.

Assuming that the plate cylinder 1 is to print from an inner plate 32, as well as from an outer printing plate 2, and that the newspaper, or other printed product, is, for example, to have seven columns, our lock-up will then be in the position shown in Fig. 3, in which the inner plate 32 cooperates with the fixed center clip 33 and with the movable inner clip 4 and the outer clip 3. When an outer plate 2 is used we preferably adjust the check nut or stop 19 on the member 8 to leave a space 34 between the stop 40 and the inner clip 4.

We employ the usual eccentric lock-up formed of a shaft 35 mounted in the lock-up plate 29, the eccentric end 36 of the shaft 35 being mounted in a shoe 37, mounted in a recess 38 in the end 39 of the hub of the plate cylinder 1. By placing the key 40 in the seat 41, formed for its reception in the end of the shaft 35, the lock-up plate 29 is caused to move to or from the plate cylinder to actuate the different clip rods 6, 6 to lock or unlock the different printing plates carried by the plate cylinder.

When the key 40 is operated, in the manner just described, to lock the outer printing plate 2 and the inner plate 32 to print a newspaper, for example, having seven columns, the parts will be in the position shown in Fig. 3, where the spring 28 is compressed between the end plate 30 and the shoulder 24 on the clip rod 6, thereby firmly but yieldingly pressing the clip rod 6 to the right, causing the threads 11 on the portion 7 cooperating with the threads 22 on the outer clip 3 to force the outer clip 3 to move to the right, and transmit the lock-

ing spring pressure of the spring 28 through the outer clip 3, outer plate 2, inner clip 4, inner printing plate 32 to the fixed center clip 33.

It will be noted that in this position of the parts that the space 34 between the stop or lock nut 19 and the inner clip 4 will prevent the stop or nut 19 transmitting any pressure to the inner clip 4, thereby permitting the entire strain of the locking spring 28 to be transmitted through the outer and inner printing plates 2 and 32 to the center fixed clip 33.

To release the printing plates 2 and 32 the eccentric lock-up is operated by the key 40 in the opposite direction to permit the lock-up plate 29, with its end plates 30, to move to the left of the position shown in Fig. 3 and into the position shown in Fig. 5, which is the unlocked position. This permits the outer and inner printing plates to be removed and replaced with other plates to print a newspaper, or other printed product, of the same width of sheet, here referred to, for purposes of description, as seven columns.

In unlocking the eccentric lock-up and with more particular reference to Fig. 5, it will be seen that when the spring 28 is released it will have a tendency to force the end plate 30' and the lock-up plate 29, on which it is mounted, so far to the left in Fig. 5, that the surface 45 on the lock-up plate 29 would engage with the surface 46 on the shoulder 24, were it not prevented from doing so. To prevent these two surfaces 45 and 46 from contacting with each other, we mount the collar 26 on the clip rod 6, which collar passes freely in the opening 47 in the end plate 30'. The coil spring 28 is sufficiently large that it not only engages with the interior surface 48 of the end plate 30', but also with the inner surface of the collar 26, when the parts are unlocked as shown in Fig. 5. This collar 26, is adjusted by the set screw 27 to a position on the clip rod 6 so that it will engage the spring 28 before the spring can bring the surface 45 on the lock-up plate 29 into contact with the surface 46 on the shoulder 24, leaving a space or clearance 50 as shown in Fig. 5.

This is particularly desirable, for if these two surfaces 45 and 46 contacted with each other under the action of the spring 28, so much friction would be developed at this point that it would be difficult for a hand tool to operate the clip rod 6.

With the parts in their unlocked position (Fig. 5), and it is desired to print a newspaper, or other printed product, of a less number of columns, as for example, six columns, all that is necessary is for the operator to rotate or screw the clip rod 6 by any suitable hand tool applied to the square end

25 of the clip rod and continue this rotation until the outer clip 3 contacts with the previously set stop or nut 13 which has previously been adjusted for a six column newspaper or other product; or adjusted for any other desired width of sheet.

At the same time that the outer clip 3 is being moved to the right by the screw-threads 11, cooperating with the threads 10 and 9 on the interior of the clip, screw-threads 10 and 9 are cooperating with each other, but as their pitch is half that of the threads 11 and 22, the portion 8 of the clip rod 6 is moved to the right only half the distance, 15 the feather 16 in the spline 15 preventing the rotation of the part 8 of the clip rod. The stops or nuts 19 and 20 on the inner member 8 of the clip rod have been previously adjusted for a six column newspaper 29 or other printed product; or adjusted for any other desired width of sheet.

The eccentric lock-up is then operated to lock up these smaller printing plates in the manner previously described.

When it is desired to operate the plate cylinder 1, without an outer plate 2, this can readily be done for the pressure of the lock-up spring 28 will be transmitted through the clip rod 6 to the stop or nut 19, and thence to the inner clip 4. With no outer plate 2, the space 34 will be eliminated by the movement of the clip rod 6 to the right of the position shown in Fig. 3.

The stop or nut 19 operates the inner clip 4 when the plate 32 is used without the outer plate 2. The nut or stop 20 withdraws the inner clip 4 from the plate 32 when the eccentric lock-up is unlocked.

In the specification and claims, reference has been made to different number of columns or different column widths, as well as to different number of columns or width of sheet to be printed. It is to be understood that these terms are meant to, 45 and do cover different lengths of stereotype plates regardless of the width of sheet, or the width of printed matter, or the number of columns. It is clear that you can print any number of columns with the same length plate and with the same width of printed matter and the same width of sheet by varying the widths of the columns. It is also possible to vary the width of the printed matter without varying the 50 length of the stereotype plates or the width of the printed sheet. In such case the width of the margin would vary, as for example, by casting a blank margin on the end of the stereotype plates. By arranging the printed matter and blank margin on the stereotype castings, it would be possible to print on different widths of sheets without varying the length of the plates. Again stereotype plates are not always cast with the 55 columns transverse to the axis of the

printing cylinder. They are often cast with the columns running parallel with the axis of the cylinder. In such cases the width of the printed matter would become the length of the columns, and a shorter or 70 longer column might necessitate a shorter or longer plate. All these uses are, and are meant to be, included in the claims.

The invention in its broader aspects is not limited to the specific mechanisms shown 75 and described but departures may be made therefrom within the scope of the accompanying claims without departing from the principles of the invention and without sacrificing its chief advantages. 80

What we claim is:—

1. A quick lock-up for plate cylinders including a spring pressed clip rod and means to neutralize the action of the spring when the lock-up is in its inoperative or 85 unlocked condition, so that the clip rod may be readily turned.

2. The combination in a quick lock-up for a plate cylinder, including a clip rod, a lock-up plate, spring means between the lock-up plate and clip rod, and means to prevent contact between the clip rod and lock-up plate, so that the clip rod may be readily turned. 90

3. The combination in a quick lock-up 95 for a plate cylinder, including a clip rod, a lock-up plate, spring means between the lock-up plate and clip rod, and adjustable means to prevent contact between the clip rod and lock-up plate, so that the clip rod may be 100 readily turned.

4. The combination in a quick lock-up for a plate cylinder, including a lock-up plate, a clip rod provided with means to normally engage one end of a spring, and means also 105 on the clip rod to engage the other end of the spring when the lock-up plate is in its unlocked position, so that the clip rod may be readily turned without frictionally engaging the lock-up plate, and a spring. 110

5. The combination in a quick lock-up for a plate cylinder, including a lock-up plate, a clip rod provided with a shoulder to normally engage one end of a spring, and a collar also on the clip rod to engage the other end of the spring when the lock-up plate is in its unlocked position, so that the clip rod may be readily turned without frictionally engaging the lock-up plate, and a spring. 115

6. In a quick lock-up for plate cylinders including a lock-up plate provided with a chamber for the reception of the end of a clip rod and spring, a clip rod having its end mounted in the chamber of the lock-up plate and provided with a shoulder to cooperate with a spring, a spring cooperating with the shoulder on the clip rod, an end plate mounted on the lock-up plate and normally contacting with the spring, and adjustable 125 130

- means mounted on the clip rod, to take the thrust of the spring in the unlocked position of the lock-up plate so that the clip rod may be readily turned.
- 5 7. In a quick lock-up for plate cylinders including a lock-up plate provided with a chamber for the reception of the end of a clip rod and spring, a clip rod having its end mounted in the chamber of the lock-up plate and provided with a shoulder to cooperate with a spring, a spring cooperating with the shoulder on the clip rod, an end plate mounted on the lock-up plate and normally contacting with the spring, and an adjustable collar mounted on the clip rod, to take the thrust of the spring in the unlocked position of the lock-up plate so that the clip rod may be readily turned. 70
- 10 8. In a quick lock-up for plate cylinders including a clip rod provided with stops to properly position the clips for different number of columns or width of sheet, clips on the clip rod, a spring, a lock-up plate, and means to neutralize the action of the spring when the lock-up plate is in its inoperative or unlocked condition, so that the clip rod may be readily turned. 80
- 15 9. In a quick lock-up for plate cylinders including a clip rod provided with exterior screw-threads, an outer clip provided with interior screw-threads to cooperate with those on the clip rod, and stops to properly position the outer clip for different number of columns or width of sheet. 85
- 20 10. In a quick lock-up for plate cylinders including a clip rod provided with exterior screw-threads, an outer clip provided with interior screw-threads to cooperate with those on the clip rod, and adjustable stops to properly position the outer clip for different number of columns or width of sheet. 90
- 25 11. In a quick lock-up for plate cylinders including a clip rod provided with exterior screw-threads, an outer clip provided with interior screw-threads to cooperate with those on the clip rod, an inner clip, and adjustable stops to properly position the outer and inner clips for different number of columns or width of sheet. 95
- 30 12. In a quick lock-up for plate cylinders including a clip rod provided with exterior screw-threads, an outer clip provided with interior screw-threads to cooperate with those on the clip rod, stops to properly position the outer clip for different number of columns or width of sheet, a lock-up plate, and a spring between the lock-up plate and the clip rod. 100
- 35 13. In a quick lock-up for plate cylinders including a clip rod provided with exterior screw-threads, an outer clip provided with interior screw-threads to cooperate with those on the clip rod, stops to properly position the outer clip for different number of columns or width of sheet, a lock-up plate, and a spring between the lock-up plate and the clip rod. 105
- 40 14. The combination in a plate cylinder printing press of a quick lock-up including a clip, a clip rod, stops to properly position the clip for different number of columns and width of sheet to be printed, and engaging means between the clip and clip rod operated by rotating the clip rod so that the clip will engage the proper stop for the particular number of columns or width of sheet to be printed. 110
- 45 15. The combination in a plate cylinder printing press of a quick lock-up including a clip, a clip rod, stops to properly position the clip for different number of columns and width of sheet to be printed, engaging means between the clip and clip rod operated by rotating the clip rod so that the clip will engage the proper stop for the particular number of columns or width of sheet to be printed, and a lock-up plate to lock the clip rod and clip. 115
- 50 16. The combination in a plate cylinder printing press of a quick lock-up including a clip, a clip rod, stops to properly position the clip for different number of columns and width of sheet to be printed, and engaging means between the clip and clip rod operated by rotating the clip rod so that the clip will engage the proper stop for the particular number of columns or width of sheet to be printed, a lock-up plate, a spring between the lock-up plate and the clip rod. 120
- 55 17. The combination in a plate cylinder printing press of a quick lock-up including a clip, a clip rod, stops to properly position the clip for different number of columns and width of sheet to be printed, engaging means between the clip and clip rod operated by rotating the clip rod so that the clip will engage the proper stop for the particular number of columns or width of sheet to be printed, a lock-up plate, a spring between the lock-up plate and the clip-rod, and means to neutralize the action of the spring when the lock-up plate is in its inoperative or unlocked condition so that the clip rod may be readily rotated. 125
- 60 18. A new article of manufacture for printing presses comprising a clip rod formed in a plurality of parts, one part being provided with exterior and interior screw-threads, and the other part being provided with exterior screw-threads to cooperate with the interior threads of the first part and stops on the respective parts to cooperate with outer and inner clips. 130
- 65 19. The combination of a quick lock-up for plate cylinders, including a clip rod provided with exterior screw-threads, an outer clip provided with interior screw-threads to

cooperate with the screw-threads on the clip rod, an inner clip, means to actuate the inner clip from the clip rod when no outer printing plate is used, said means being inoperative when an outer printing plate is employed, and stops to properly position the inner and outer clips for different number of columns or width of sheet to be printed. 5

20. The combination of a quick lock-up 10 for plate cylinders, including a clip rod provided with exterior screw-threads, an outer clip provided with interior screw-threads to cooperate with the screw-threads on the clip

rod, an inner clip, means to actuate the inner clip from the clip rod when no outer printing plate is used, said means being inoperative when an outer printing plate is employed, stops to properly position the inner and outer clips for different number of columns or width of sheet to be printed and a 20 lock-up plate. 15

In testimony whereof, we have signed our names to this specification.

WILLIAM EVENSEN.
GEORGE L. HERMANSON.
